UNITED STATES PATENT OFFICE.

CHARLES E. SOULE, OF SOMERVILLE, MASSACHUSETTS, ASSIGNOR OF ONE-THIRD TO
FRANK PAGE BEARSE AND ONE-THIRD TO WILLIAM THOMAS ABBOTT, BOTH OF
WINCHESTER, MASSACHUSETTS.

ANTIRATTLING DEVICE.

1,327,291.

Specification of Letters Patent.

Patented Jan. 6, 1920.

Application filed November 25, 1918. Serial No. 263,948.

To all whom it may concern:

Be it known that I, CHARLES EDWARD SOULE, a citizen of the United States, and a resident of Somerville, in the county of 5 Middlesex and Commonwealth of Massachusetts, (whose post-office address is No. 2 Carver street, Somerville, Massachusetts,) have invented an Improvement in Anti-rattling Devices, of which the following 10 description, in connection with the accompanying drawings, is a specification, like characters on the drawings representing like parts.

This invention relates to improvements 15 in hood fasteners for automobiles and more particularly to improved means for preventing the side of the hood from rattling.

The invention has for its object among 20 other things to provide means of the general character referred to that may be produced as relatively low cost, that is efficient in operation and simple in construction and that may be readily and quickly applied to the hood fastener without removing or dis- 25 mounting the latter or any part thereof.

These and other objects of the invention will be readily understood from the following description taken in connection with the 30 accompanying drawings of one form of the invention selected for the purpose of illustration it being understood that the invention in its true scope is definitely set forth by the claims.

In the drawings: 35 Figure 1 is a side elevation of a hood fastener showing the selected illustrative embodiment of my invention in operative position;

Fig. 2 is a sectional view, partially in 40 elevation, of the parts shown in Fig. 1;

Fig. 3 is a cross section on line 3—3 of Fig. 1;

Fig. 4 is a front view thereof;

Fig. 5 shows a top plan view of a modi- 45 fication of the device shown in Fig. 1.

The side of an automobile hood, of ordinary and usual construction, is shown at 2, said part 2 being provided with the usual projecting member 4 of any suitable construction provided at the top with a recess or notch 6 to be engaged by the hook-shaped projection 8 of the hood fastener. The latter may be of any suitable and usual construction. Herein it is shown as comprising

a cylindrical portion or body 10 with the 55 top of which the handle 12, bearing the hook-shaped projection 8 above referred to has screw-threaded connection at 14. At its lower end the body 10 is provided with a restricted opening 16 through which extends with a sliding fit a rod 18, the upper end of which is provided with a guiding collar 20 within said body, while the lower end of said rod is provided with a rounded or ball-shaped portion 22 received within a 60 socket member 24 upon a plate 26 forming a part of the automobile frame, thus forming a ball and socket or swivel mounting for said fastener. Within the body 10 the rod 18 is surrounded by a spring 28 having 70 bearing at one end against the lower end wall of said body and at its upper end against the collar 20.

A member, such as a flange 30, which may be secured to the plate 26 or may be integral therewith and extends along the lower edge of the side 2 of the hood inside the latter when the hood is closed, is provided to prevent the side of the hood from swinging inwardly, and the spring connection of the rod 18 with the body 10 of the fastener is such that in order to cause the hook-shaped projection 8 to engage the notch 6 of the member 4, said body must be raised relatively to said rod, thus putting 80 the spring 28 under tension, said spring remaining under tension during such engagement and thus holding the side of the hood down as will be readily understood by those skilled in the art. 90

It is well known that the sides of hoods thus held or secured are liable to rattle and in order to prevent this I have conceived means one embodiment of which will now be described. Herein said means comprises a body portion 32, which may be of any suitable construction, and which is provided with any suitable means for removably securing the device to the body 10 of the fastener, and with means to bear against 95 the side of the hood when the device is in operative position, said bearing means herein preferably consisting of a pad 34 of yielding material. In the embodiment of the invention shown the body portion 32 100 of the device and the means removably to secure the latter to the body 10 of the hood fastener are preferably made integral and 105

may consist of a plate of spring metal shaped substantially as shown in Fig. 3, so as to form a holding having the inturned flanges 36, 36 to receive between them and 5 securely hold the removable pad 34, and a clamp having the semi-cylindrical clamping plates 38, 38 provided with the outturned flanges 40, 40 at their free ends. By pressing the outturned flanges 40, 40 longitudinally against the body 10 of the fastener, said flanges will yield outwardly to allow said body to be embraced by the semi-cylindrical clamping plates 38, 38 of spring metal, thus firmly but removably securing 10 said device to said fastener body 10 substantially in the position shown in Fig. 1. In that position, when the hook-shaped projection 8 of the fastener is in engagement with the projecting member 4 of the side 15 of the hood, the pad 34 of the device will bear against the side 2 of the hood, thus firmly holding the lower edge of the side or the hood against the flange 30 of the plate 20 26 and prevent rattling of the parts.

25 It will be readily understood by those skilled in the art that the metal body portion of the device can be easily stamped and shaped from spring metal, thus enabling the device to be manufactured at low cost. It 30 will also be seen that the device can be easily and quickly attached to or removed from the fastening devices in common use for holding down the sides of the hood, and this without dismounting said fastener or separating or removing any part thereof. While the action of the clamping plates 38, 38 is amply sufficient to prevent accidental 35 removal of the device from the fastener, the engagement of the pad 34 of the device 40 with the side of the hood when said device is in operative position renders such accidental removal impossible. The device also has the advantage of being adjustable longitudinally of the fastener, thus enabling it 45 to be quickly located at that point where it will bear with the greatest effect against the side of the hood, and when in operative position said device will efficiently prevent rattling of the parts.

50 Instead of being made integral, the pad-holding flanged portion of the device and the clamping plates 38, 38 may each be made of a separate piece of sheet metal, in which case the latter only need be of spring metal. 55 These two parts may then be spot-welded or otherwise secured to each other. Such a modified construction is shown in Fig. 5.

60 It will be apparent to those skilled in the art that devices constructed in accordance with the present invention possess advantages other than those specifically referred to herein. It is also to be understood that while I have herein described two specific embodiments of my invention, the invention 65 is not to be considered as limited to the de-

tails described, nor any of them, but that said embodiments may be variously modified within the true scope of my invention, which is more particularly set forth in the claims.

Claims.

1. The combination with the side of an automobile hood, a fastener for the latter and a member to engage the side of the hood upon one side when the hood is closed, of a device comprising means to removably secure it to said fastener and means to engage the side of the hood upon the opposite side from that engaged by said member, when said fastener is in operative position. 70

2. The combination with the side of an automobile hood, a fastener for the latter and a member to engage the side of the hood on one side when the hood is closed, of a device to be carried by said fastener comprising means to engage the side of the hood upon the opposite side from that engaged by said member, when said fastener is in operative position, and means whereby said device can be secured to said fastener without removing the latter. 80

3. The combination with the side of an automobile hood, a fastener for the latter and a member to engage the side of the hood on one side when the hood is closed, of a device to be carried by said fastener comprising means to engage the side of the hood upon the opposite side from that engaged by said member, when said fastener is in operative position, and means including opposed semi-cylindrical resilient clamping members whereby said device can be secured to said fastener without dismounting the latter. 95

4. The combination with the side of an automobile hood, a fastener for the latter and a member to engage the side of the hood upon one side when the hood is closed, of a device comprising means to removably secure it to said fastener and a pad to engage the side of the hood upon the opposite side from that engaged by said member, when said fastener is in operative position. 100

5. The combination with the side of an automobile hood, a fastener for the latter and a member to engage the side of the hood upon one side when the hood is closed, of a device comprising means to removably secure it to said fastener and a removable pad to engage the side of the hood upon the opposite side from that engaged by said member, when said fastener is in operative position. 115

6. A device of the class described to be carried by the fastener of the side of an automobile hood, comprising, in combination, clamping means to secure said device to said fastener and means to engage the side of the hood when said fastener is in operative position. 125

7. A device of the class described to be carried by the fastener of the side of an automobile hood, comprising, in combination, means to engage the side of the hood when said fastener is in operative position; holding means therefor; and means secured to said holding means for securing the device to said fastener.
8. A device of the class described to be carried by the fastener of the side of an automobile hood, comprising, in combination, a pad to engage the side of the hood when said fastener is in operative position; metal holding means therefor; and a spring metal clamp spotwelded to said holding means for securing the device to said fastener.
9. A device of the class described to be carried by the fastener of the side of an automobile hood, comprising, in combination, a pad to engage the side of the hood when said fastener is in operative position; metal holding means therefor; and a spring metal clamp spotwelded to said holding means for securing the device to said fastener.
10. A device of the class described to be carried by the fastener of the side of an automobile hood, comprising, in combination, a pad to engage the side of the hood when said fastener is in operative position; metal holding means therefor; and a spring metal clamp spotwelded to said holding means for securing the device to said fastener.

In testimony whereof, I have signed my name to this specification.

CHARLES E. SOULE.
